UNITED STATES PATENT OFFICE.

RAY M. MURRAY, OF BILLINGS, MONTANA.

REVERSIBLE FAN.

1,384,672.

Specification of Letters Patent. Patented July 12, 1921.

Application filed March 15, 1919. Serial No. 282,830.

To all whom it may concern:

Be it known that I, RAY M. MURRAY, a citizen of the United States, and a resident of Billings, county of Yellowstone, and State 5 of Montana, have invented a new and Improved Reversible Fan, of which the following is a full, clear, and exact description.

My invention relates to devices such as propellers.

rically through the shaft. This pin also extends through a sleeve 7 encircling the tubular shaft 3 and movable bodily thereon in the direction of the length of the shaft. The 60 parts are so arranged that the shaft 8 may be moved in the direction of its length by shifting the pin 6 carrying with it the sleeve 7.

Located within the tubular shaft 3 and 65

3.8. El ligno, que tiene un porcentaje de lignina del 10-15%, es un material de combustible que se obtiene de la madera.

110. Fig. 22 is a section on line A-A of Fig. 11, showing the side of the iron.

By virtue of the above, the *Explanatory Memorandum* is hereby submitted for your kind consideration.

adjusted angularly in relation to such shaft, as required, at the will of the operator.

A screw bolt 25 detachably mounted upon the portion 16 of the tubular shaft 3 normally retains the casing 11 in position.

The operation of my device is as follows:

Power being applied to the pulley 12 by means of a belt, or the like, the case 11 and the parts carried by it are rotated in a manner well understood in this art. As this takes place the blades 23 may be any desired pitch allowed by the limits of travel of the grooved wheel 19—that is, travel in the direction of the axis of rotation. With the parts in the positions indicated in Fig. 1, the blades 23 have no inclination or pitch whatever. If, however, the sleeve 7 be moved to the right, according to Fig. 1 so that the annular guide 19 is shifted to the right according to this figure, the blades 23 are tilted or given pitch in one direction; and if the sleeve 7 be shifted so that the grooved wheel 19 moves to the left according to Fig. 1, the blades are given a pitch in the opposite direction. Thus the operator, by noting the position of the sleeve 7 and moving this sleeve to the right or left, according to Fig. 1, may vary within reasonable limits, the pitch of the blades 23. Each time the sleeve 7 is moved into its middle position, as indicated in Fig. 1, the blades are brought to their neutral position indicated in Fig. 1. But if the sleeve 7 be shifted in either direction from this middle position, the blades are each tilted or given a different pitch accordingly, all of the blades being actuated in the same manner at the same time.

I do not limit myself to the precise mechanism shown, as variations may be made therefrom without departing from the spirit of my invention, the scope of my invention being commensurate with my claims. Neither do I limit myself to any particular material to be employed in making my device, nor to any special use for which the device may be employed.

Having thus described my invention what I claim as new, and desire to secure by Letters-Patent is as follows:

1. A device of the character described, comprising a bracket, a stationary tubular shaft carried thereby and provided with

55 pairs of opposed slots near opposite ends thereof, a pin extending through one pair of said slots, a stationary shaft located within said tubular shaft and movable bodily in the direction of the length thereof, another pin carried by said last mentioned shaft and extending through the other pair of slots, 60 a grooved wheel mounted on the first named shaft over the last named slots and receiving the second named pin therethrough, a revoluble casing on said tubular shaft and inclosing a portion of the same and said 65 grooved wheel and second named pin, a blade carried by said revoluble casing, and adjustable angularly in relation thereto, and mechanism connected with said blade and with said grooved wheel for enabling axial 70 adjustment of said wheels to adjust the pitch of the blade.

2. A device of the character described, comprising a bracket, a stationary tubular shaft carried thereby and provided with 75 pairs of opposed slots near opposite ends thereof, a pin extending through one pair of said slots, a stationary shaft located within said tubular shaft and movable bodily in the direction of the length thereof, another pin carried by said last mentioned shaft and extending through the other pair of slots, 80 a grooved wheel mounted on the first named shaft over the last named slots and receiving the second named pin therethrough, a revoluble casing on said tubular shaft and inclosing a portion of the same and said 85 grooved wheel and second named pin, a plurality of radial blades carried by said revoluble casing, said casing being provided with bearing sleeves receiving the 90 blades for angular adjustment therein with reference to the casing and the axis of the shafts, a removable head on the end of the casing, said casing being adapted to receive 95 suitable lubrication, means to prevent displacement of the casing with respect to the tubular shaft, crank members connected with said blades for changing the pitch thereof, and rollers carried by said crank members 100 and engaging said grooved wheel for the purpose of enabling said wheel to change the relative positions of said crank members by shifting the pin and second named shaft longitudinally within the tubular shaft.

RAY M. MURRAY.
